MECHANISM FOR WINDING PAPER INTO ROLLS

Application filed August 30, 1929, Serial No. 389,404, and in Canada June 28, 1929.

This invention relates to mechanism for winding paper webs into rolls, and has reference more particularly to such mechanisms as are used to handle the paper web delivered 5 continuously from paper making machines. Mechanisms for this purpose are now being used, one for instance being known as the English type reel, and comprise a drum known as under or driving drum with which 10 two winding reels are mounted to co-operate, the web being wound on the reels alternately; when one reel is filled, the web is severed and the new length fed onto the empty reel, the filled reel being removed and an empty 15 reel substituted in its place.

Our invention consists of a mechanism of this general type, but of improved form in which the continuous web to be rolled is wound alternately on two winding reels 20 operating with and driven by the under drum, the web being severed when one of the reels is filled and the new length of web, following severance, automatically directed to and wound around the other reel, and the 25 web again severed when the latter reel is filled, the next new length being automatically directed to an empty reel which has in the meantime been substituted for the first filled reel; the operation of severing the web 30 is repeated, so that the web is fed automatically to and wound around the reels alternately and without interruption.

Our improved mechanism results in and has for prime objects, the almost complete 35 elimination of waste of paper web or stock arising now under known mechanisms, saving in labor and machine production time, substitution of unskilled for skilled labor and a reduction of dangers and hazards incident 40 to the operation of known machines.

In the specification to follow, our improved mechanism is described in detail, and the novel features thereof pointed out in the appended claims.

45 In the drawings:

Figure 1 is a side elevation of a winding mechanism of the type known as the English reel (with parts removed), improved so as to constitute our invention;

50 Figure 2 is a fragmentary top plan view

showing air blast devices and cutting device initiating the severance of the web, parts of the mechanism being shown in dot and dash lines;

55 Figure 3 is a fragmentary top plan view of the cutting device;

Figure 4 shows lip or incision made in the web by the operation of the cutting device;

60 Figure 5 is a fragmentary side elevation showing portion of one of the air blast devices.

Like numerals of reference indicate corresponding parts in the various figures.

Referring by numerals to the drawings, 65 and more particularly to Figure 1, our mechanism comprises essentially an under drum 10, two winding reels 11 and 12 on which severed portions of the continuous web 13 are wound alternately, and for which similar winding reels are substituted when these 70 are completely filled, a device 14 for initiating the severance of the web, a fluid blast device 15 to act on the new lengths of the severed web and adjustable to direct said lengths alternately to the two reels, and a 75 second fluid blast device 16 associated with the under drum and operable to direct the new length of web carried by the drum onto the reel 12.

80 The rotary drum 10 is journaled in suitable bearings 17 in a frame 18 and is driven from any source of power (not shown), usually an electric motor connected to the drum shaft with suitable reduction gears provided 85 therebetween.

83 The reels 11 and 12 have end journals 11a and 12a respectively, turning in slotted ends 19 in the reel carrying arms 11b and 12b respectively. The arms 12b are journaled at 90 their lower ends to rock on studs 12c on the ends of the horizontal transverse member 20 fixed in the frame 18, so that the winding reel supported in the upper ends of said arms can move to and from the under drum, 95 thereby permitting the empty winding reel to contact with the drum at the beginning of the winding of the web thereon, as shown in Figure 1, and permitting said winding reel 100 to gradually move away from the drum as

the diameter of the roll of paper increases as the winding operation progresses.

The arms 11b are similarly journaled at their lower ends on studs 11c on the ends of 5 the rear horizontal transverse supporting member 20a extending parallel to the supporting member 20 and fixed in the frame 18, whereby the winding reel 11 supported in the upper ends of said arms, is permitted to 10 swing to and from the drum for the same purpose as the corresponding action of the reel 12.

The paper web 13 coming continuously from the last pass of a calender stack of a 15 paper making machine, (not shown) passes beneath and around a segmental guiding surface 21 fixed to the transverse supporting member 20a between the two arms 11b, and from this guiding surface the web passes into 20 the bite of the winding reel 11 and the drum 10. The web is first wound on the winding reel 11, and when this reel becomes filled and the web is severed so as to separate the wound web from the unwound web, the new 25 length of the latter is then directed to the empty winding reel 12 to be wound thereon, and when this reel becomes filled, the web is again severed, and the succeeding new length is directed to an empty winding reel which 30 was in the meantime substituted for the filled reel 11.

The severance of the web is initiated by the device 14 before alluded to, which as shown in Figure 1 is located to act on the web at a 35 point ahead of the bite of the reel 11 and drum 10, and preferably just after the web passes around the guiding surface 21. As best shown in Figures 2 and 3, this device may comprise a horizontal blade 22 which is piv- 40 oted at one end on a vertical axis as at 23, to a bracket 24 fixed to a strap 25 clamped to the supporting member 20a, the free end of the blade being pointed or sharpened so that when engaged with the traveling web, the 45 latter will be broken or cut. By the mounting of the blade in this manner, it may be swung from an inactive position free of the traveling web, to an active position in the path of the web to engage the same. The 50 blade is thus actuated by means of an operating rod 26 mounted to slide endwise in guides 27 fixed at intervals to the supporting member 20a, which rod extends at its outer end to the front of the machine frame, where it is 55 provided with a handle 26a for operating it. At its inner end the rod is provided with a pin 27a engaging in a longitudinal slot 28 in the blade, and by pushing the rod rear- 60 wardly, the blade will be swung rearwardly and engage with the traveling web, and then by the forward movement of the rod, the 65 blade will be disengaged from the web.

The engagement of the blade with the trav- 65 eling web and the continued movement of the blade to engaging and again disengaging

positions while the web is traveling forward will result in an incising or tearing of the web in two diagonal lines 29 and 29a, whereby there will be formed in a web a lip of paper 30 separated from the main portion, and as 70 this lip travels forwardly between the drum 10 and the winding reel 11 and as it emerges from the bite of these members, it is acted on by the fluid blast device 15, which by its adjustments will operate either to hold the lip 75 against the winding reel or against the drum, according as to whether the new length of web is to be directed to one or the other of the two winding reels. In either case, the 80 lip being held against the members or folded back by the action of the blast, the continued movement of the web due to its winding action, will cause the incision made by the blade to extend clear across the web and thereby completely sever the same. To insure that a 85 lip may be preferably formed as just mentioned, it is preferable that the movement of the rod 26 be limited in one direction and this is accomplished by suitably spacing the 90 clamp 25 from the pin 23 so that the knife 90 is not disengaged from the web while in its rearwardmost position, shown as 22A in Figure 3.

The fluid blast device 15 is located at the upper side of the under drum and between 95 the two winding reels, as best shown in Figure 1, and it may consist of a horizontal supply pipe 32 mounted to rock in a larger pipe 32B supported in bearings in the upper ends of two standards 33 rising above the bearings 100 17 of the under drum, the said pipe being supplied with fluid under pressure, preferably air, from any suitable source, and being provided about midway of its length with a number of air discharging nozzles 34 directed 105 to the right as viewed in Figure 1 whereby by the rocking of the pipe 32, the air blasts issuing from the nozzles may be caused to impinge either on the winding reel 11 or upon the under drum 10.

The blast pipe 32 is rocked to thus adjust the blast nozzles, by means of an adjusting lever 34A fixed to the pipe 32 at the front of the machine and provided with a locking dog 35 adapted to engage in notches 36 and 37 in a 110 segment plate 39 fixed to the forward stand- 115 ard 33. When the locking dog is engaged in the notch 36 (dotted position of lever in Figure 1) the blast nozzles will be held so as to impinge their blasts against the drum; and when the locking dog is engaged in the upper 120 notch 37, (lever shown in full lines) the blast nozzles will be held so as to impinge their blasts on the reel 11. When the blasts are so impinged, they will rebound, the blasts 125 when directed against the winding reel rebounding toward the under drum, and when directed against the under drum, rebounding towards the winding reel, so that when the separated lip on the web emerges from the bite 130

of the winding reel 11 and under drum, and follows with the web as the latter is wound on the winding reel, the blasts in acting on the winding reel will detach the lip therefrom 5 and in rebounding will throw the lip down on the under drum, and holding the lip against the under drum, the rotation of the latter in co-operation with the rotation of the winding reel, will sever the wound portion 10 of the web from the unwound portion, and the latter will be carried around by the under drum towards the winding reel 12 to be wound thereon. When now the winding reel 12 becomes filled with the new length of 15 web, and it is desired to sever the web and direct the following new length to the winding reel 11, the nozzles are adjusted so as to direct the blasts against the under drum, with the result that the newly formed lip on the 20 web as it is carried around by the under drum and reaches the blast impinging thereon, will be lifted from the drum and the rebounding blast will carry it towards and press it against the new empty winding reel 11, substituted 25 for the former filled reel, thereby severing the web as before and causing it to wind upon the new reel 11.

It is seen therefore that by the successive operations of the blade 22, and the adjustments of the blast nozzles, the new lengths of 30 web may be caused to pass alternately to the winding reels.

It will be understood that in these successive operations, the blade is moved rearwardly 35 and forwardly, and the blast nozzles are set in their different positions only long enough to effect the complete severance of the web, and the feed of the new lengths to the respective reels, whereupon the supply of the blast 40 fluid is cut off.

When the air blasts are directed against the filled winding reel 11 in order to throw the detached lip on the web down on the under drum 10, the new length of web after the 45 severance of the same, will be carried around the drum 10 past the empty reel 12, and will continue on down with the drum, and in order to detach the end of this new length from the drum and direct it to the empty winding 50 reel 12, a doctor knife 38 is provided which bears constantly against the surface of the drum and will act to lift the end of the new length of web therefrom, and this new length is blown upwardly onto the empty winding 55 reel 12 by the blast device 16 before alluded to. This blast device 16 may consist of supply pipes 37 provided about midway of its length with blast nozzles 38A directed upwardly and tangentially to the surface of the 60 drum and towards the winding reel 12 and end nozzles 38B positioned to impinge their blasts under the ends of the web. The pipe 37 is supplied with pressure fluid, preferably air, from a suitable source, and the blast is 65 turned on only momentarily; and when the

end of the new length is directed onto the winding reel 12 by the blast, the latter is turned off.

It will be understood that when the winding reels become filled, they will be removed 70 from their supporting arms 11b and 12b respectively, and empty and similarly winding reels will be substituted, so that there will always be an empty winding reel engaged 75 with the drum and ready to receive the new length of web when the latter is severed.

From the foregoing description, it will be seen that the operations of winding the continuous web onto the two winding reels will take place continuously without interrupting the travel of the web, the attendant, as the winding reels become alternately filled with the web, operating the blade 22 and the fluid blasts 15 and 16 at intervals as the two winding reels are alternately filled. As a result there will be no interruption in the action of the mechanism, which will operate with efficiency and dispatch in the winding of the continuous web and without loss of material or time.

In the foregoing description and accompanying drawings, the invention is set forth as embodying certain detailed forms and arrangements of the parts, but it will be understood that these details may be variously changed and modified by the skilled mechanic without departing from the limits of the invention; and further, it will be understood that the invention is not limited to any particular form or construction of the parts, except in so far as such limitations are specified in the claims; further that while for purposes of demonstration and disclosure we have chosen the English type reel, it is to be understood that our invention can be embodied in other types of reels.

What we claim as our invention is:

1. In a paper winding mechanism, the combination of a rotary drum, arms pivotally mounted at points equi-distant from the axis of said drum and on each side thereof, winding reels journaled in said arms for engagement with said drum and adapted to have paper webs wound thereon alternately, means for delivering a paper web into the bite of one of said reels and said drum, means for initiating the severance of said web at a point ahead of said bite to separate the unwound webs from the wound webs, and fluid blast means releasably locked in either of two alternate positions whereby to impinge its blast on said rotary drum and one of said reels alternately.

2. In a paper winding mechanism, the combination of a rotary drum, arms pivotally mounted at points substantially equi-distant from the axis of said drum and on each side thereof, winding reels journaled in said arms for engagement with said drum and adapted to have paper webs wound thereon alternate-

ly, means for delivering a paper web into the bite of one of said reels and said drum, a reciprocable knife mounted at a point ahead of said bite and between the edges of said web operable to incise said web whereby a lip is formed, and releasably locked fluid blast means operable to direct its blast in either of two directions alternately whereby the lip and said drum are impinged by said blast alternately.

3. In a paper winding mechanism, the combination of a rotary drum, two winding reels, a forward and a back reel, supported to be rotated by said drum and adapted to have paper webs wound thereon alternately, means for delivering a web of paper into the bite of the forward one of said winding reels and said drum, means for initiating the severance of the web at a point ahead of said bite to separate the wound web from the unwound web when a winding reel becomes filled, fluid blast means adapted to act on the forward end of the unwound web and operable to detach the same from the filled reel and cause said end to be carried to the empty winding reel, and a second fluid means in position to direct the forward end of the unwound web from the drum onto the rear winding reel.

30 4. In a paper winding mechanism, the combination of a rotary drum, two winding reels, a forward and a back reel, supported to be rotated by said drum and adapted to have paper webs wound thereon alternately, means for delivering a web of paper into the bite of the forward one of said winding reels and said drum, means for initiating the severance of the web at a point ahead of said bite to separate the wound web from the unwound web when a winding reel becomes filled, fluid blast means adapted to act on the forward end of the unwound web and operable to detach the same from the filled reel and cause said end to be carried to the empty winding reel, and wound around the empty reel if a forward reel, and a second fluid means in position to direct the forward end of the unwound web from the drum onto the rear winding reel.

5. In a paper winding mechanism, the combination of a rotary drum, two winding reels, a forward and a back reel, supported to be rotated by said drum and adapted to have paper webs wound thereon alternately, means for delivering a web of paper into the bite of the forward one of said winding reels and said drum, means for initiating the severance of the web at a point ahead of said bite to separate the wound web from the unwound web when a winding reel becomes filled, fluid blast means variable in direction adapted to act on the forward end of the unwound web and operable to detach the same from the

filled reel and cause said end to be carried to the empty winding reel.

6. In a paper winding mechanism, the combination of a rotary drum, two winding reels, a forward and a back reel, supported to be rotated by said drum and adapted to have paper webs wound thereon alternately, means for delivering a web of paper into the bite of the forward one of said winding reels and said drum, means for initiating the severance of the web at a point ahead of said bite to separate the wound web from the unwound web when a winding reel becomes filled, fluid blast means variable in direction adapted to act on the forward end of the unwound web and operable to detach the same from the filled reel and cause said end to be carried to the empty winding reel, and wound around the empty reel if a forward reel, and a second fluid means in position to direct the forward end of the unwound web from the drum onto the rear winding reel.

7. In a paper winding mechanism, the combination of a rotary drum, two winding reels journaled for engagement with said drum and adapted to have paper webs wound thereon alternately, means for delivering a web of paper into the bite of the forward one of said winding reels and said drum, means for initiating the breaking of the web at a point ahead of said bite when a winding reel becomes filled, fluid blast means operable to act on the said broken point of the web after it has passed said bite and complete the separation of the unwound web from the web being wound on a forward reel and to press the unwound end down against the rotary drum to be carried to the rear winding reel, and a second fluid blast means in position to direct the end of the web after it has passed the rear winding reel from the rotary drum onto said rear winding reel so as to be wound thereon.

Signed at the city of Ottawa, Canada, this 15th day of August, 1929.
